CASING HEAD EQUIPMENT

Lewis Mervyn Cecil Seamount, St. Just, England

Application September 20, 1930, Serial No. 483,290
and in Great Britain March 29, 1930

44 Claims. (Cl. 166—14)

This invention relates to casing head equipment for bore holes.

The invention has among its objects to provide simple and effective means by which casing or tools of varying size or form used in sinking bore holes may be passed into and be withdrawn from the bore hole, and the tools rotated, without escape of oil or gas, and by which boring may be continued before and after high pressures have been encountered and without loss at the surface of oil or gas under the pressures prevailing.

According to the invention the casing head equipment for bore holes or wells comprises a casing, a massive elastic sleeve within the casing through which the connected lengths of the boring tool or the parts required to be lowered into the bore hole may be passed, and means by which the respective ends of the sleeve are positively held but are capable of relative axial movement, by which the internal contraction of the sleeve is permitted under pressure of a fluid pressure medium externally applied to the sleeve, which medium may be derived from the well or elsewhere. By such means substantially liquid and gas tight joints are maintained under varying conditions of operation.

According to the invention, moreover, the sleeve is reinforced to prevent excessive deformation on its internal contraction; the housing or casing of the sleeve also is adapted to permit of rotation; the rotatable housing or casing of the sleeve is adapted also to permit of a slight gyratory movement during the rotation of the boring tool and the rotatable housing or casing is mounted or suspended between anti-friction bearings adapted to resist upward and downward stresses.

The invention also comprises the features hereinafter described.

The invention is diagrammatically illustrated by way of example in the accompanying drawings in which

Figure 1 is a sectional elevation of a rotary blow-out preventer constructed according to the invention;

Figures 1a and 1b are respectively elevation and plan of a suitable reinforcement that may be provided for the elastic sleeve employed;

Figure 1c is an enlarged sectional view showing the manner in which a joint is made at the upper and lower ends of the rotating casing;

Figure 1d is a sectional elevation of a rotary blow-out preventer similar to that illustrated in

Figure 1, in which the fastening ring is moulded in the elastic sleeve;

Figure 1e is a detail view of the fastening ring illustrated in Figure 1d;

Figure 2 is a so-called sleeve packer constructed according to the invention, and

Figure 3 is a sectional elevation of a modification of rotary blow-out preventer constructed according to the invention.

In carrying the invention into effect according to the construction illustrated in Figure 1, an outer cylindrical casing *a* is provided which is secured to the well head flange *a*¹ by means of a bayonet flange *r* in known manner, and upon the casing *a* a cover *g* is applied having a cylindrical part *g*¹ adapted to be mounted upon the externally screw-threaded upper part of the casing. The elastic sleeve *d* is mounted between end rings *e*¹, *e*⁴ having oppositely disposed annular cavities within which the respective ends of the sleeve are held.

The end ring *e*¹ (Figure 1) is made integral with the lower end of the trunnion tube *e*. The flange thus formed engages beneath a massive shoulder *u*¹ at the upper end of the rotating casing *u*. A number of pins *e*⁵ are provided on the upper face of the end ring *e*¹, parallel with the axis of the tube *e* in determined position coincident with corresponding holes in the shoulder *u*¹. A connection is thus made of the trunnion tube *e* with the rotating casing *u*, by which axial displacement of the end ring *e*¹ and trunnion tube *e* is permitted in relation to the casing *u*. The casing *u* encloses the sleeve *d* and has transversely disposed holes *u*² through which a fluid pressure medium may find access to the external surface of the sleeve *d*. Thus pressure may be applied to cause the contraction of the sleeve *d* to maintain a fluid tight joint between the sleeve and the boring tool or the like. The end ring *e*⁴ extends within the lower screw-threaded end of the casing *u* and serves firmly to hold the lower end of the sleeve *d*; and similar means are provided to secure the upper end of the sleeve *d* within the end ring *e*¹.

The end ring *e*⁴ (Figure 1) has an annular cavity on its under face for the upper reduced screw-threaded part of a bottom ring *e*⁶, the lower part of which extends completely across the end ring and is screw-threaded in position, and thus forms a contact face by which a horizontal joint is provided between the lower end of the casing *u* and the base part *a*² of the casing.

The casing *u* (Figure 1) has at its upper end

an outwardly extending flange u^3 to serve for the suspension of the casing u from the cover g , and by which the upward thrust is taken when pressures are encountered in the operation of boring. Ball bearings k^1 , k^2 are provided above and beneath the flange u^3 , which permit the casing u a slight eccentric or gyratory movement during the rotation of the boring tool. For this purpose a flat ring g^2 is set within the cover g immediately over the flange u^3 , so as to fit against the horizontal face or shoulder g^3 , while a second ring g^4 is adjustably disposed beneath the flange u^3 , screw-threaded on its outer periphery, the ball bearing k^2 being here interposed.

A fibre jointing ring g^5 of a V or other similar sectional shape is fitted beneath the second ring g^4 and between the upper outer peripheral bevelled edge of the casing u and the cover g . The casing u has a gland ring u^4 screw-threaded within an annular cavity of the casing u and the flange of the gland ring comes to lie over the ring g^2 and serves as a horizontal jointing face. An annular cavity g^6 is formed on the under face of the cover g for the packing g^7 . The top part of the cover g extends short of the trunnion tube e to accommodate the slightly gyratory movement referred to and to permit of access to a packing ring u^5 of conical cross-section between the ring u^4 and the tube, and a screw-threaded retaining ring u^6 is applied upon the packing ring u^5 .

The base part a^2 of the casing a (Figure 1) is provided with an annular cavity a^3 for the reception of packing g^7 . Surrounding this cavity a^3 on the face of the base part a^2 , another cavity is provided for the reception of a jointing ring a^4 , the top face of which extends slightly above the normal face of the base part a^2 .

An annular space v (Figure 1) is provided between the casing u and the casing a , by which the slight gyratory movement of the casing u is accommodated and means are provided for the admission of a fluid pressure medium such as that derived from the well or such as water from a hydraulic accumulator, under regulation, so that thus the required pressure may be applied within the annular space v upon the sleeve d , so that it may be contracted to maintain an effective liquid and gas tight joint between the sleeve d and the parts of the boring tool or the like held in or passing through the sleeve. The packing g^7 consists of rings or turns of packing of a kind commonly employed for hydraulic work; they are applied upon an annular indiarubber sheet g^8 whose edges are retained in position by metal rings g^9 . Channels or passages a^5 and g^{10} through the outer parts of the casing and the cover g respectively are provided for conveying the fluid pressure medium to the inner faces of the packing in order to make a tight joint. An upwardly extending flange g^{11} on the casing g is screw-threaded externally and a cap i is screw-threaded thereon. A ring i^1 is screw-threaded on the trunnion tube e , and this ring has packing rings i^2 and i^3 on its upper and lower faces respectively and one of the packing rings is adapted to contact with the underside of the cap while the other packing ring is adapted to contact with the top face of the cover g depending upon the position of the ring i^1 . The ring i^1 has a spring arm i^4 which is adapted to be engaged in one of a number of vertical grooves on the tube e whereby the ring may

be retained in any adjusted position on the tube e .

A drive bush fitting e^{11} (Figure 1) is mounted upon the tube e , having a hole e^{12} for the reception of the Kelly or grief stem of the same section; and the lower part of the fitting e^{11} and the upper part of the trunnion tube e are provided with interengaging parts. The fitting e^{11} is held in position by means such as a number of spring arms e^{13} that engage a ring e^{14} threaded upon the upper end of the tube e .

To fasten the ends of the elastic sleeve d (Figure 1) within the end rings e^1 , e^4 , a fastening ring e^7 of tubular form is employed for insertion within an annular recess in each of the end rings, the annular recesses opening into the annular cavities in the end rings concentric therewith. The cross-section of the rings e^7 is reduced near the outer end, and is enlarged at the outer ends where they have faces inclined inwards towards the reduced part of the cross-section. An annular cavity generally corresponding in cross-section to that of the fastening ring is provided at the ends of the sleeve d , the depth of which is substantially less than that of the respective fastening rings, so that thus on the latter being inserted into the cavities in the sleeve, the outer ends of the rings protrude beyond the sleeve. A number of screw-threaded pins e^8 disposed equidistant are inserted in the end rings e^1 , e^4 , so that their stems pass into the respective annular recesses in the end rings, and engage within screw-threaded holes in the fastening rings set therein, recesses e^9 being provided on the outer face of the end rings for the accommodation of the heads of the pins e^8 . On the rotation of the pins e^8 the ring e^7 is drawn into the annular recess in the corresponding end ring, and the outer enlarged rim of the fastening ring is thus caused to move towards the end ring, and thus the inclined faces of the enlarged rim cause pressure to be applied upon the substance of the sleeve d in positions between the enlarged rim and the circumferential edges e^{10} , whereby the ends of the sleeve d are very securely held. The pins e^8 are set apart intermediate of the pins e^5 .

With a view to prevent excessive inward movement of the sleeve d under the pressure externally applied the sleeve may be reinforced. The reinforcement may as in Figures 1, 1a and 1b consist of two or more rings such as w of wire, formed of twisted strands. Two coincident rings w may be set near the respective ends of the sleeve d , so as to lie in position on the inner side of the annular cavities provided at the ends of the sleeve d for the rings e^7 . The rings w are connected together by wire w^1 formed of twisted strands, and arranged zig-zag, the wire w^1 being disposed obliquely, and the whole having externally applied near the ends of the frame thus formed, a covering of wire netting w^2 to extend inwards to a small extent to form a cylindrical band of netting at the respective ends. Thus a reinforcement is provided which when used in the moulding of the elastic sleeve d from indiarubber, offers a resistance to abnormal deformation of the sleeve under the stresses imposed externally upon it in the use of the equipment.

The fastening ring e^7 may as shown in Figures 1d and 1e, be moulded in the sleeve, being formed with a number such as six, parallel integral bolts e^{15} by which the ends of the sleeve d are secured within the cavities in the end

- rings e^1 , e^4 , the bolts having screw-threaded ends which in the case of the end ring e^1 extend through the ring into recesses e^9 for the reception of nuts e^8 . In the case of the end ring e^4 which, in the assembly of the parts requires to be rotated relatively to the casing a for the engagement therewith of its screw-thread, the bolts e^{15} are caused to engage in corresponding holes e^{17} in a slip ring e^{16} adapted to be seated in a corresponding annular recess formed in the upper face of the end ring. The depth of the slip ring is such that the bolts e^{15} do not project completely through it, and the holes e^{17} are enlarged in diameter in the lower face of the slip ring for the reception of suitable socket nuts e^{18} , which when the end ring e^4 has been adjusted in position are passed from the underside through corresponding holes e^{19} to engage the bolts e^{15} . The holes e^{19} are formed with a shoulder upon which the part of the nuts e^{18} of larger diameter may seat and thus on the rotation of the nuts the bolts e^{15} are drawn firmly to seat the sleeve d in the end ring. The latter may be provided with the same number of holes e^{17} as there are bolts e^{15} or with a multiple of such number so that the possible adjusted positions of the end ring are increased in number. This means of engagement of the bolts e^{15} with the end ring may also be applied to the upper end ring e^1 .
- The reinforcement w (Figure 1d) may consist of strands of wire passed over the retaining rings e^7 and suitably secured to the rings as for example by welding or otherwise. The construction illustrated in Figure 1d may be otherwise the same as that illustrated in Figure 1.
- The downward movement of the trunnion tube e (Figures 1 and 1d) may be produced by causing the weight of the tools to be taken upon the trunnion tube. By such means the sleeve d will be compressed and thus the application of fluid pressure around the sleeve d may be dispensed with as in the construction of a packer as in Figure 2 when rotation of the sleeve is not required.
- The stationary casing a (Figure 2) may be supported upon a base fitting a^6 secured to the well head flange. The base fitting may have its cylindrical upper part externally screw-threaded for insertion within the lower end of the casing a , an internal screw-thread being provided at the lower end of the casing a for the purpose. The elastic sleeve d is secured at its respective ends within end rings e^1 and e^4 , one of which e^4 may be formed integral with the base fitting a^6 , while the end ring e^1 fits within the casing a and has an external annular recess e^{15} adapted for the packing x^1 on which a gland ring x may be applied. Pressure may be applied axially upon the gland ring by means of a screw-threaded ring x^2 . The sleeve d may be contracted as in the construction hereinbefore described to make a tight joint with the sections of boring tool or other parts on the external application of hydraulic or other fluid pressure, under regulation; the fluid pressure medium being passed through the inlet c^1 into the jacket c in the casing, passing through holes c^2 around the elastic sleeve; or the sleeve may be contracted by allowing the weight of the casing or tools to be passed through it to act on the gland ring x .
- In carrying the invention into effect as illustrated in Figure 3 the elastic sleeve d is mounted at each end within tubular trunnion fittings e , whereby an integral unit e d e may be mounted within the casing a to be rotatable therein on anti-friction bearings k . The trunnion fittings e e are enlarged in diameter at the parts e^1 so that a shoulder is formed between which and the inner ends of the rings g and h , the bearings k are interposed, and annular cavities e^2 provided for the reception of the ends of the elastic sleeve d . For the purpose anchoring bolts l are adapted at their screw-threaded ends to be engaged by nuts l^1 within obliquely disposed cavities e^3 . The bolts l are embedded in the substance of the sleeve d and provided with enlarged parts or heads l^2 and so disposed at an angle for example of 30° to the vertical, that they pass through the respective cavities e^2 and through the parts of the sleeve therein.
- The supporting rings g h (Figure 3) serve as stuffing box housings for the parts e e . The ring g is provided with an annular space for the gland packing m , and a gland ring i which encloses the outer end of the ring g . The outer flange of the gland ring is internally screw-threaded to engage the externally screw-threaded upper part of the ring g .
- An internal screw-thread is formed upon the part g^1 to engage an external screw-thread at the upper end of the casing a ; the internal screw-thread is however discontinued short of the end thereof, and near the end an external screw-thread is provided for engagement with an external jointing ring j having at its lower end an inwardly extending flange j^1 between which and the end of the part g^1 , packing j^2 is provided. The ring h extends into the lower part of the casing, and is formed with an extension provided with bayonet projections h^2 adapted to engage in corresponding parts of the surrounding base fitting r which is secured to the well head fitting b . An external jointing ring n is engaged between a conical end face of the casing a and a conical face formed upon a shoulder of the ring h at the enlarged lower part extending beneath the casing.
- Similar means to those immediately hereinbefore described for maintaining a tight joint may be provided between the lower supporting ring h and the lower tubular trunnion fitting e , as illustrated in Figure 3, that is to say an elastic sleeve o of indiarubber may be subjected to fluid pressure by which its inner face may be pressed into contact with a part of the lower trunnion fitting e in such manner however as to permit rotation. One or more passages h^1 parallel with its axis may be provided in the ring h , to extend from the upper face of the ring to a position beside a narrow annular cavity formed on the inner face of the ring, in which the sleeve o may be mounted. Surrounding this cavity a perforated cylindrical ring p may be mounted within the ring h , and behind this, a narrow cavity may be formed with which the passage or passages h^1 communicate, and by which the pressure prevailing between the casing a and the main sleeve d may be transmitted to the sleeve o . The sleeve o has a substantially dovetail vertical cross-section, and is held by means of bearing or retaining rings q , q^1 secured in position upon the supporting ring h . The lower ring q^1 may be held in position by means of an externally screw-threaded ring q^2 applied within the lower end of the supporting ring h ; a retaining nut e^4 may be applied in an adjacent position upon the end of the lower trunnion fitting e .
- Means may be provided for the independent supply and control of the pressure fluid for the

5 sleeves *d* and *o* under such conditions that the rotation of the unit *e d e* (Figure 3) is substantially freely permitted; or again a pin or other inlet valve *s* may be provided by which the pressure fluid may be cut off from access to the sleeve *o*. Such a valve *s* may be mounted so as to be conveniently operable by a handle or spanner. Furthermore relief valves such as *t* may be provided. That for the pressure fluid supplied for 10 the elastic sleeve *o* may be provided as a ball valve.

15 The manner of operation is similar in the respective constructions of Figures 1, 1*d* and 3 and any fluid pressure medium such as liquid, air or steam may be employed, or a hydraulic accumulator may be employed loaded by weights or by pressure in the bore hole or elsewhere to exert pressure upon the fluid medium employed. In 20 operation of the equipment of Figure 3 the fluid pressure medium is admitted at a determined pressure through the inlet piping *c*¹, jacket *c* and holes *c*² into the annular space *f* to compress the sleeve *d*, and the pressure medium is confined by the packed joints, adjustments being made for 25 ensuring tight joints as for example between the supporting rings *g* and *h* and the trunnion fittings *e*.

30 Boring tools and other parts of circular cylindrical or other form or of varying diameter, are adapted to pass through an elastic sleeve *d* (Figures 1, 1*d*, 2 and 3) in the casing without leakage of oil or gas under the pressure that may at the time prevail in the bore hole. Should it be required to leave in the bore hole without further 35 movement, part of the drill stem or other part within the casing or sleeve, and still maintain the pressure in the bore hole, then by vertical movement of the upper trunnion tube or fitting *e* (Figures 1, 1*d*, 3) which can be effected under 40 the weight of the parts being passed through the sleeve, the latter may be compressed axially, and thus pressure from the hydraulic accumulator may be dispensed with. Should the weight be insufficient to compress the sleeve for example 45 in the construction of Figure 3 for the purpose of forming a seal between itself and the casing and between itself and the parts being passed through the sleeve, the upper supporting ring *g* may be moved downwards to effect the seal; and the gland ring *i* at the upper end of the upper supporting ring *g*, and the jointing ring *j* externally mounted upon it, may be adjusted to effect permanent seals against leakage from between the sleeve and the casing or bore hole, and the upper 50 protruding end of the upper tubular trunnion fitting *e* may be provided with means adapted for the operation by a spanner or other tool; and the gland ring *i*, the upper supporting ring *g* and the external jointing ring *j* may also be adapted for 55 operation by similar means.

60 The invention is adapted for use without provision for rotation of the elastic sleeve *d* (Figure 3) in which case the tubular end fittings *e* are not necessarily provided as trunnions nor are they adapted to rotate, but the uppermost supporting ring may be supported for axial movement for the axial compression of the elastic sleeve if and when required. Furthermore the provision of the sleeve *o* (Figure 3) may be dispensed with and the lower trunnion fitting *e* may be mounted within the supporting ring in a manner similar to the upper trunnion fitting.

65 The reinforcement of the elastic sleeve may take any other form than those specifically described. It is however in general preferred to

provide the reinforcement and to connect the reinforcement to the respective end rings. Thus also any other packing on the horizontal jointing faces provided in the construction illustrated in Figures 1 and 1*d* may be employed by which gas and liquid tight joints may be provided, and by which the gyratory movement of the rotating parts may be accommodated. The elastic sleeve is provided massive, and when provided to rotate as for example in constructions such as illustrated in Figures 1, 1*d* and 3, the sleeve is provided relatively long.

70 I claim:—

1. A casing head equipment, comprising a stationary casing, a massive elastic sleeve within 90 the casing, annular elements having annular cavities respectively provided therein, adapted for the reception of the respective ends of the said sleeve and not being adapted for relative rotation, one of said annular elements being axially 95 movable and the other being axially immovable, means for securing the respective ends of the said sleeve within the said annular cavities, comprising fastening rings concentrically held within the respective ends of the sleeve, and means by 100 which the said fastening rings may be respectively drawn towards the respective annular elements to secure the ends of the said sleeve in the respective annular cavities therein.

105 2. A casing head equipment, comprising a stationary casing, connected parts within the stationary casing adapted to rotate together therein to constitute a rotor, the rotor comprising a massive elastic sleeve through which the sections and couplings of the drilling tool or casing may 110 pass, means upon the said stationary casing for the suspension therein of the rotor, the rotor being free for limited gyratory movement, means for the application of pressure external to the said sleeve for causing its internal contraction, 115 and packing between the rotor and the said stationary casing.

120 3. A casing head equipment comprising a stationary casing, connected parts within the stationary casing adapted to rotate together therein to constitute a rotor, the rotor comprising a massive elastic sleeve through which the sections and couplings of the drilling tool or casing may 125 pass, means upon the said stationary casing for the suspension of the rotor therein, comprising supporting surfaces respectively upon the stationary casing and upon the rotor, the rotor having clearance within the stationary casing to permit of gyratory movement thereof, anti-friction bearings disposed between 130 the said surfaces by which the rotor is supported against upward and downward stresses and is permitted rotary and gyratory movements, means for the application of pressure external to the sleeve for causing its internal contraction, and 135 packing between the rotor and the stationary casing.

140 4. A casing head equipment comprising a massive elastic sleeve, a stationary casing within which the sleeve is mounted, means for mounting the sleeve within the stationary casing comprising a rotating casing and annular elements within the rotating casing, one of which is axially movable but incapable of relative rotation with respect to the rotating casing, while the 145 other element is axially immovable with respect to the rotating casing.

150 5. A casing head equipment comprising a stationary casing, a rotating casing within the stationary casing, a massive elastic sleeve within

- the rotating casing and anti-friction bearings between which the rotating casing is suspended to resist upward and downward stresses, means on the stationary casing for the admission there-
5 in of a fluid pressure medium, and means on the rotating casing to render the fluid pressure me-
dium accessible to the external surface of the sleeve.
6. A casing head equipment comprising a sta-
10 tionary casing, a rotating casing within the sta-
tionary casing, a massive elastic sleeve within the rotating casing, anti-friction bearings between which the rotating casing is suspended to resist upward and downward stresses, means on the
15 stationary casing for the admission therein of a fluid pressure medium, means on the rotating casing to render the fluid pressure medium ac-
cessible to the external surface of the sleeve, a cap for the closure of the upper open end of the
20 stationary casing, and means to maintain fluid tight joints between the parts of the rotating casing and the parts of the stationary casing and the cap.
7. A casing head equipment comprising a sta-
25 tionary casing, a massive elastic sleeve, a hous-
ing for the sleeve within the stationary casing, anti-friction bearings upon which the housing is supported to resist upward and downward stresses, means upon the stationary casing by
30 which a fluid pressure medium may be admitted therein, means to render the fluid pressure me-
dium accessible to the external surface of the sleeve, and means to maintain fluid tight joints between the parts of the housing and the parts
35 of the stationary casing.
8. A casing head equipment comprising a sta-
tionary casing, a rotating casing adapted to have a gyratory movement within the stationary cas-
ing, a massive elastic sleeve within the rotating
40 casing, anti-friction bearings upon which the ro-
tating casing is supported to resist upward and downward stresses, horizontal jointing faces at the upper and lower ends of the stationary and rotating casings, expandible packing between the
45 horizontal jointing faces and means by which a fluid pressure medium is admitted within the stationary casing and behind the expandible packing.
9. A casing head equipment comprising a sta-
50 tionary casing, a rotating casing adapted to have a gyratory movement within the stationary cas-
ing, a massive elastic sleeve within the rotating casing, the sleeve having an internal reinforce-
55 ment adapted to resist the excessive internal con-
traction of the sleeve on the application of fluid pressure external to the sleeve, means by which the rotating casing is supported to resist upward and downward stresses, annular elements within
60 which the ends of the sleeve are held within the rotating casing, means upon the stationary casing by which a fluid pressure medium may be admitted therein, means to render the fluid pressure me-
dium accessible to the external surface of the sleeve, and means to maintain fluid tight joints
65 between the parts of the rotating casing and the parts of the stationary casing.
10. A casing head equipment comprising a sta-
tionary casing, a massive elastic sleeve, a hous-
70 ing for the sleeve within the stationary casing, anti-friction bearings upon which the housing is supported to resist upward and downward stresses, a gland ring applied at the upper end of the housing, a cap for the open end of the stationary cas-
ing, expandible packing between the top of the
75 said gland ring and the cap and between the lower end of the housing and the lower part of the sta-
tionary casing, means upon the stationary casing by which a fluid pressure medium may be admitted therein, and means to render the fluid pres-
sure medium accessible to the external surface of the sleeve.
11. A casing head equipment comprising a sta-
tionary casing, a massive elastic sleeve, a housing for the said massive elastic sleeve within the sta-
tionary casing, annular elements adapted for con-
nection of the respective ends of the sleeve with-
in the housing, one of said annular elements be-
ing axially movable while being not adapted for
relative rotation with respect to the other annular element, reinforcement for the sleeve adapted
to resist excessive inward contraction thereof,
fastening rings respectively at opposite ends of the sleeve to which the respective ends of the re-
inforcement are connected, means for securing
the respective ends of the sleeve and the respec-
tive fastening rings to the respective annular ele-
ments, anti-friction bearings for supporting the
said housing, means upon the stationary casing by which a fluid pressure medium may be admitted
therein, means to render the fluid pressure me-
dium accessible to the external surface of the sleeve, and means to maintain fluid tight joints
between the parts of the housing and the parts
of the stationary casing.
12. A casing head equipment comprising a sta-
tionary casing, a massive elastic sleeve, a hous-
ing for the sleeve within the stationary casing, anti-friction bearings upon which the housing is supported to resist upward and downward stresses,
a gland ring applied at the upper end of the hous-
ing, a cap for the open end of the stationary cas-
ing, expandible packing between the top of the said gland ring and the cap and between the lower end of the housing and the lower part of the sta-
tionary casing, means upon the stationary casing by which a fluid pressure medium may be admitted therein, means to render the fluid pres-
sure medium accessible to the external surface of the sleeve, and a jointing ring upon the lower part of the stationary casing, the top face of which jointing ring extends slightly above the normal jointing face.
13. A casing head equipment comprising a cas-
ing, a massive elastic internal-jointing sleeve within the casing through which the connected sections and couplings of the drilling tool or cas-
ing may pass under substantially pressure tight conditions, means for resisting excessive internal contraction of the sleeve on the application of fluid pressure external to the sleeve, comprising a reinforcement embedded within the sleeve, the internal contraction of which is permitted at a position between its ends, means by which the respective ends of the reinforcement are held in opposition to the fluid pressure externally ap-
plied to the sleeve and means for the applica-
tion of fluid pressure external to the sleeve.
14. A casing head equipment comprising a cas-
ing, a massive elastic internal-jointing sleeve within the casing through which the connected sections and couplings of the drilling tool or cas-
ing may pass under substantially pressure tight conditions, annular elements adapted for the con-
nection of the respective ends of the sleeve, means for resisting excessive internal contraction of the sleeve on the application of fluid pressure ex-
ternal to the sleeve, comprising a reinforcement embedded within the sleeve, the internal con-
traction of which reinforcement is permitted at a position between its ends, means for securing

the ends of the sleeve and of the reinforcement to the annular elements, and means for the application of fluid pressure external to the sleeve.

15. A casing head equipment comprising a massive elastic internal-jointing sleeve, a casing within which the sleeve is contained, means for mounting the upper end of the sleeve to be axially movable and the lower end to be axially immovable, said means comprising fastening rings 10 engaging the respective ends of the sleeve, and means for the application of fluid pressure external to the sleeve.

16. A casing head equipment comprising a casing, a massive elastic sleeve within the casing, means by which the massive elastic sleeve is mounted with its respective ends held, the said ends being capable of relative axial movement under pressure external to the sleeve, and means for the application of pressure external to the 20 sleeve.

17. A casing head equipment comprising a casing, a massive elastic sleeve within the casing, annular elements in which the respective ends of the sleeve are mounted within the casing, one of 25 the annular elements being adapted to have axial movement within the casing under pressure externally applied to the sleeve, and means for the application of pressure external to the sleeve.

18. A casing head equipment comprising a casing, a massive elastic sleeve within the casing, a housing for the said sleeve within the casing adapted to permit of rotation of the sleeve within the casing, and means by which the massive elastic sleeve is mounted within the housing with 30 its respective ends held the upper end of the said sleeve being capable of relative axial movement under pressure externally applied to the sleeve, and means for the application of pressure external to the sleeve.

40 19. A casing head equipment comprising a casing, a massive elastic sleeve, a housing for the said sleeve adapted to rotate within the casing, a cap applied to the upper open end of the casing from which the housing is suspended, means by which the massive elastic sleeve is mounted 45 with its respective ends held within the housing, the upper end of the said sleeve being capable of relative axial movement under pressure applied external to the sleeve and means for the application of pressure external to the sleeve.

50 20. A casing head equipment comprising a casing, a massive elastic sleeve within the casing, means by which the sleeve is mounted with its respective ends held, the upper end of the 55 said sleeve being capable of relative axial movement under pressure external to the sleeve, means for resisting excessive internal contraction of the sleeve on the application of pressure external to the sleeve, comprising a reinforcement embedded within the sleeve, the internal contraction of which reinforcement is permitted at a position between its ends, and means for the application of fluid pressure external to the sleeve.

60 65 21. A casing head equipment comprising a casing, a massive elastic sleeve within the casing, annular elements in which the respective ends of the sleeve are mounted within the casing, the upper annular elements being adapted to have axial movement within the casing under pressure externally applied to the sleeve, means for resisting internal contraction of the sleeve on the application of pressure external to the sleeve, 70 comprising a reinforcement embedded within the 75

sleeve, the internal contraction of which reinforcement is permitted at a position between its ends, and means for the application of fluid pressure external to the sleeve.

80 22. A casing head equipment comprising a massive elastic sleeve, a stationary casing within which the sleeve is mounted, means comprising a trunnion tube for mounting the sleeve to rotate within the stationary casing and annular elements, one of which is axially movable and formed integral with the trunnion tube but is incapable of relative rotation with respect to the other, while the other is axially immovable.

85 23. A casing head equipment comprising a massive elastic sleeve, a stationary casing within which the sleeve is mounted, means for mounting the sleeve within the stationary casing comprising a rotating casing and annular elements within the rotating casing, one of which is axially movable but is incapable of relative rotation with respect to the other, while the other annular element is axially immovable.

90 24. A casing head equipment comprising a stationary casing, a massive elastic sleeve, a housing for the sleeve adapted to rotate within the stationary casing, axially immovable anti-friction bearings at each end of the housing upon which the housing is supported to resist upward and downward stresses, means by which the respective ends of the sleeve are held, the upper end of the sleeve being capable of relative axial movement under pressure externally applied to the sleeve, and means for the application of pressure external to the sleeve.

100 25. A casing head equipment comprising a stationary casing, a massive elastic sleeve, means for mounting the sleeve to rotate within the stationary casing, axially immovable anti-friction bearings upon which the means for mounting the sleeve are supported to resist upward and downward stresses, means by which the respective ends of the sleeve are held, the upper end of the sleeve being capable of relative axial movement under pressure externally applied to the sleeve, and means for the application of pressure external to the sleeve.

110 26. A casing head equipment comprising a packer, a rotor within which the said packer is mounted, a stationary casing for the reception of the rotor, means to permit a free gyratory movement of the rotor within the casing, comprising a cavity within the stationary casing having a diameter substantially larger than the external diameter of the rotor to yield a free annular space within the cavity and surrounding 120 the rotor within which the rotor is rotatable eccentrically of the normal axis or centre line of the casing head.

125 27. A casing head equipment comprising a packer, a rotor within which the said packer is mounted, a stationary casing for the reception of the rotor, means to permit a free gyratory movement of the rotor within the stationary casing, comprising a cavity within the stationary casing, the parts of which are of a larger diameter 130 than the corresponding peripheral parts of the rotor to yield communicating spaces in the respective parts of the cavity and surrounding the rotor within which the peripheral parts of the rotor rotate eccentrically of the normal axis or 140 centre line of the casing head.

135 28. A casing head equipment comprising a massive elastic sleeve, a rotatable housing for the sleeve, and a stationary casing for the reception of the said housing, the said stationary casing 145

- having a cavity therein, the said cavity being of larger diameter than the said housing, the said housing comprising an axially movable tubular member whose upper end extends beyond the stationary casing, and means at the upper end of the tubular member for bearing the weight of tubing depending in the well. 5 means to render the trunnion tube incapable of relative rotation with respect to the housing. 7
37. A casing head equipment, consisting of a casing, a massive elastic internal jointing sleeve within the casing through which the connected sections and couplings of the drilling tool or casing may pass under substantially pressure tight conditions, annular elements, for the reception of the respective ends of the sleeve, and means for resisting excessive internal contraction of the sleeve on the application of pressure external to the sleeve, comprising a reinforcement embedded within the sleeve and means for securing the ends of the said reinforcement within the said annular elements, and means for the application of pressure external to the sleeve. 80
38. A casing head equipment, consisting of a casing, a massive elastic internal jointing sleeve within the casing through which the connected sections and couplings of the drilling tool or casing may pass under substantially pressure tight conditions, annular elements for the reception of the respective ends of the sleeve, means for resisting excessive internal contraction of the sleeve on the application of pressure external to the 85 sleeve, comprising reinforcement embedded within the sleeve permitting the internal contraction of the sleeve at a position between its ends under the resistance of the reinforcement and of the sleeve in compression, means for securing the ends of the reinforcement within the annular elements, comprising fastening rings embedded in the respective ends of the sleeve to which the ends of the reinforcement are respectively connected, and means for the application of pressure external to the 90 sleeve. 95
39. A casing head equipment consisting of a casing, a massive elastic internal jointing sleeve within the casing through which the connected sections and couplings of the drilling tool or casing may pass under substantially pressure tight conditions, annular elements for the reception of the respective ends of the sleeve, means for resisting internal contraction of the sleeve on the application of pressure external to the sleeve, 100 comprising reinforcement embedded within the sleeve and held at its respective ends against the pressure externally applied to the sleeve, means for securing the ends of the reinforcement within the respective annular elements comprising 105 fastening rings embedded in the respective ends of the sleeve to which the ends of the reinforcement are respectively connected, and means for connecting the respective fastening rings to the 110 respective annular elements. 115
40. A casing head equipment, comprising a stationary casing, a massive elastic sleeve and a housing for the said sleeve within the said casing and adapted to rotate therein, said housing comprising a trunnion tube adapted for relative axial movement against the resistance of the sleeve. 120
- 45 33. A casing head equipment, comprising a stationary casing, a massive elastic sleeve and a housing for the said sleeve within the said casing and adapted to rotate therein, said housing comprising a trunnion tube adapted for relative axial movement against the resistance of the sleeve. 125
- 50 34. A casing head equipment, comprising a stationary casing, a massive elastic sleeve and a housing for the said sleeve within the said casing and adapted to rotate therein, said housing comprising trunnion tubes, the uppermost of which is adapted for axial movement with reference to the sleeve, the other being immovable axially. 130
- 55 35. A casing head equipment, comprising a stationary casing, a massive elastic sleeve and a housing for the said sleeve within the said casing and adapted to rotate therein, said housing comprising trunnion tubes, the uppermost of which is adapted for axial movement with reference to the sleeve, the other being immovable axially, and anti-friction bearings by which the housing is supported to resist upward and downward axial stresses. 135
- 60 36. A casing head equipment, comprising a stationary casing, a massive elastic sleeve and a housing for the said sleeve within the said casing and adapted to rotate therein, said housing comprising trunnion tubes, the uppermost of which is adapted for axial movement with reference to the sleeve, the other being immovable axially, and
- means to render the trunnion tube incapable of relative rotation with respect to the housing. 7
- 65 37. A casing head equipment, consisting of a casing, a massive elastic internal jointing sleeve within the casing through which the connected sections and couplings of the drilling tool or casing may pass under substantially pressure tight conditions, annular elements, for the reception of the respective ends of the sleeve, and means for resisting excessive internal contraction of the sleeve on the application of pressure external to the sleeve, comprising a reinforcement embedded within the sleeve and means for securing the ends of the said reinforcement within the said annular elements, and means for the application of pressure external to the sleeve. 80
- 70 38. A casing head equipment, consisting of a casing, a massive elastic internal jointing sleeve within the casing through which the connected sections and couplings of the drilling tool or casing may pass under substantially pressure tight conditions, annular elements for the reception of the respective ends of the sleeve, means for resisting excessive internal contraction of the sleeve on the application of pressure external to the 85 sleeve, comprising reinforcement embedded within the sleeve permitting the internal contraction of the sleeve at a position between its ends under the resistance of the reinforcement and of the sleeve in compression, means for securing the ends of the reinforcement within the annular elements, comprising fastening rings embedded in the respective ends of the sleeve to which the ends of the reinforcement are respectively connected, and means for the application of pressure external to the 90 sleeve. 95
- 75 39. A casing head equipment consisting of a casing, a massive elastic internal jointing sleeve within the casing through which the connected sections and couplings of the drilling tool or casing may pass under substantially pressure tight conditions, annular elements for the reception of the respective ends of the sleeve, means for resisting internal contraction of the sleeve on the application of pressure external to the sleeve, 100 comprising reinforcement embedded within the sleeve and held at its respective ends against the pressure externally applied to the sleeve, means for securing the ends of the reinforcement within the respective annular elements comprising 105 fastening rings embedded in the respective ends of the sleeve to which the ends of the reinforcement are respectively connected, and means for connecting the respective fastening rings to the 110 respective annular elements. 115
- 80 40. A casing head equipment, comprising a stationary casing, a rotor within the said casing, a packing device within the rotor and adapted to be contracted under pressure externally applied, means for the application of pressure externally to the packing device, bearing surfaces for the said rotor, packers for the said bearing surfaces within annular cavities in parts of the said stationary casing adjacent the said bearings. 120
- 85 41. A casing head equipment, comprising a massive elastic internal jointing sleeve through which the connected sections and couplings of the drilling tool or casing may pass under substantially pressure tight conditions, a casing for the sleeve, an annular element disposed above the sleeve, the said annular element being adapted for axial movement for the compression of the said sleeve under the weight of the connected sections and couplings of the drilling tool or casing. 140
- 90 42. A casing head equipment, comprising a 145

stationary casing, a rotor within the said casing, a packing device within the rotor adapted to be contracted under axial pressure, an annular element disposed within the said rotor above the said sleeve, the said annular element being adapted to have an axial movement with reference to the rotor.

43. A casing head equipment, comprising a stationary casing, a rotor within the casing, a packing device within the rotor and adapted to be contracted, means for the application of pressure external to the packing device, bearing surfaces for the said rotor, packers for the said bearing surfaces, means for supporting the rotor within the stationary casing, comprising anti-friction bearings, the rotor comprising a tubular element disposed above the packing device

adapted on downward axial movement for the compression of the packing device.

44. A casing head equipment, comprising a packer, a rotor within which the said packer is mounted, a stationary casing for the reception of the rotor, means to permit of free gyroscopic movement of the rotor within the casing comprising a cavity within the casing having a diameter substantially larger than the external diameter of the rotor to yield a free annular space within the cavity and surrounding the rotor within which the rotor is rotatable eccentrically of the normal axis or centre line of the casing head and horizontal fluid-tight joints between the rotor and the casing.
